UNITED STATES PATENT OFFICE.

TAUBE DAVIS, OF NEW YORK, N. Y., ASSIGNOR TO FRANKLIN SIMON & CO. INC., OF NEW YORK, N. Y., A CORPORATION OF NEW YORK.

DESIGN FOR A DRESS.

Application filed August 12, 1926. Serial No. 18,705. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Dress, of which the following is a specification, reference being had to the accompanying drawing, forming part thereof, wherein the dress is distinguished by a skirt having a corrugated surface and a tunic or jumper having ornamental sections extending from the yoke to the bottom of the tunic with the pile of the fabric lying in different directions for each

ornamental section, together with a belt near the lower end of the tunic having an ornamental slave chain section.

Figure 1 is a front view of a dress, showing my new design.

Figure 2 is an enlarged sectional view through Figure 1 on line 2—2.

Figure 3 is a sectional view through Figure 1 on line 3—3.

Figure 4 is an enlarged fragmentary sectional view through Figure 1 on line 4—4.

I claim:

The ornamental design for a dress, substantially as shown and described.

TAUBE DAVIS.
